UNITED STATES PATENT OFFICE.

JAMES G. WARREN, OF PROVIDENCE, RHODE ISLAND.

BOTTLE-FILLING MACHINE.

SPECIFICATION forming part of Letters Patent No. 644,219, dated February 27, 1900.

Application filed March 4, 1898. Renewed August 16, 1899. Serial No. 727,445. (No model.)

To all whom it may concern:

Be it known that I, JAMES G. WARREN, of the city and county of Providence, in the State of Rhode Island, have invented a certain new and useful Improvement in Bottle-Filling Machines; and I declare the following to be a specification thereof, reference being had to the accompanying drawings.

Like letters and numerals indicate like parts.

Figure 1 is a side elevation of my improved bottle-filling machine. Fig. 2 is a top plan and section as seen on line *a a* of Fig. 1. Fig. 3 is an enlarged view in central longitudinal section of the supporting-tube, marked *b* in Fig. 1, with its connected parts. Fig. 4 is a front elevation of my improved bottle-filling machine, the crate containing the bottles being shown in vertical section. Fig. 5 is an enlarged central section of the foam-controller, marked *c* in Fig. 4. Fig. 6 is a perspective view of the float-supporting tube, marked *d* in Fig. 5. Figs. 7 and 8 are detail views of the adjusting-plate, marked *e* in Fig. 4. Fig. 9 is a side elevation of the supply-keg and its pipes and is intended to be continuous of Fig. 4. Fig. 10 is an enlarged central section of the bung-starter, marked *f* in Fig. 9, and shows in section the pipes and couplings in combination therewith. Fig. 11 is an enlarged longitudinal section of one of the filling-tubes and the centering-bell and frame, the bottling-valve, and one of the discharge-ports of the bottle-filling tank. Fig. 12 is a rear elevation of my improved bottle-filling machine. Fig. 13 is an enlarged sectional view showing a portion of the frame, the bottle-filling tank, the centering-bells and frame, and the crate for the bottles, with the divider and its actuating mechanism, the bottles and the movable shelf being in side elevation. Fig. 14 is a view, partly in side elevation and partly in vertical section, of my improved machine when the bottles and crate are partially raised in position. Fig. 15 is a rear elevation of a part of the machine, showing the position of the valves and the valve-actuating mechanism after the bottling operation has been completed. Fig. 16 shows in elevation the lifting-finger for raising the divider and the spring for holding said finger in place when the divider is in its highest position. Fig. 17 is the same with the

finger depressed and the divider in its lowest position. Fig. 18 is an enlarged partial view of my machine, showing the bottle-filling tank and its supply pipe and valves, as also the divider, in vertical section on line *n n* of Fig. 19 and the reservoir, bottling-valves, centering-bells and frame in front elevation. Fig. 19 is a top plan of the bottle-filling tank with the cover removed, which is marked *i* in Fig. 18, the pipes for supplying said tank, and the divider, which is marked *h* in Fig. 13. Fig. 20 is a top plan of the bottling-valves and their actuating mechanism as seen in line *m m* of Fig. 18. Fig. 21 is an enlarged central vertical section of the measuring-tank and its displacement-piston, the bottle-filling tank, and the pipes and valves between them and the divider in its elevated position in the bottle-filling tank.

My invention relates to machines for filling a number of bottles simultaneously and equally with any liquid, and it is especially useful in the bottling of liquids which foam or effervesce.

My invention consists in the novel construction and combination of the several elements or parts hereinafter particularly described, and specifically set forth in the claims.

In the drawings the frame of the machine is shown at 1 and constitutes a proper standard or support. At the top of said frame is a receptacle or tank adapted to receive the liquid from a suitable source of supply and to discharge said liquid into bottles. This tank is preferably oblong and rectangular in shape, as seen in Figs. 13 and 18, and has a flange 2, Fig. 13, extending outwardly from its upper edge, which flange on the back is bent downward at a right angle, as shown at 3 in Fig. 13. This tank 4 has its sides inclined inwardly, as shown in section in Figs. 13 and 18, and in its lower portion its walls are thickened and formed so that their surfaces on the inside of the tank are at right angles with the top edge of the tank in a vertical or downward direction. The tank 4 is secured upon the top of the frame or standard 1 by bolts 5, which pass through the rear flange 2 of said tank into said frame or standard, as illustrated in Fig. 13, while the bent portion of the flange shuts down upon the upper plane surface of the frame or standard, as there

seen. Bolts 6 also pass through the frame or standard into the thickened portion near the bottom of said tank.

An oblong rectangular rim or open frame 7 is fastened by bolts 8 to the flange 2 of the tank and has its inner edge cut away to form a continuous depression, in which a plate 9 of glass rests, as seen in Figs. 13 and 18. The glass plate 9 is secured in position by the open frame or rim 10, fastened to the frame 7 by bolts 11, as shown in said figures. This glass plate serves not only to exclude dust and foreign substances from the liquid within the tank, but to allow a full unobstructed view 15 of the contents of the tank, and makes the tank air-tight and saves the gases, so that they may flow back through the vent-pipes into the keg or source of supply. From the tank a vent-pipe 12 extends upwardly. The 20 tank 4 comprises not only these inclined walls or sides, but also a bottom plate 13, of peculiar construction, which is illustrated in said Figs. 13 and 18. In the drawings this bottom portion 13 of the tank has an outwardly- 25 extending flange 14 and any suitable number of quadrangular sockets or depressions 15, each of which sockets or depressions has its four sides beveled or converging toward the center like an inverted pyramid. These 30 sockets or depressions of the tank-bottom are arranged in series, preferably as shown in the drawings, Fig. 18, in four rows of six each. Each socket or depression 15 has a port or opening 16, as seen in Figs. 13 and 18. This 35 bottom plate 13 is secured to the walls of the tank by means of its flange 14 of said bottom plate, which is bolted, as shown at 17, to a bottom flange 18 of said tank.

Within the tank 4 is a vertically-movable 40 device 19, which I designate the "divider." It is a box-like structure open at top and bottom and divided by partitions into compartments of equal size. The sides and partitions are arranged rectangularly, with the partitions at right angles with the sides and equidistant, all together constituting a series of open compartments corresponding in size and arrangement with the sockets or depressions of the bottom plate 13 of the tank. The bottom 45 of the divider 19 rests upon the inwardly-extending portion of the flange 14 of the bottom plate 13, and thus the vertical movement of the divider 19 is limited thereby in a downward direction.

50 Two lifting rods or shafts 20 are mounted in the tank 4 at 21 and 22 and extend through sleeves 23 of the standard or frame 1. Said lifting rods or shafts 20 extend across the tank 4, on the inside thereof, from back to 55 front and derive a partial rotary movement from mechanism hereinafter described. Each rod or shaft 20 has two lifting fingers or cams 24 fastened thereto.

On the top edge of the divider 19 are mounted 60 four friction-rollers 25, at or near the corners thereof, and four other friction-rollers 26 are mounted upon the sides of the divider

19 a short distance below the first-mentioned rollers, respectively, as shown in Fig. 18. The lifting fingers or cams 24 are in operative 70 contact with said rollers 25 26, respectively; as best shown in Figs. 16 and 17.

Beneath the bottom plate 13 and in a plane substantially parallel therewith are the bottling-valves 27, Fig. 11, which allow the flow 75 of the liquid from the tank through the filling-tubes into the bottles 28. These valves are most plainly shown in top plan in Fig. 20.

A rock-shaft 29 is mounted in suitable bearings beneath the bottom 13 of the tank 4, 80 (see Fig. 20,) and receives a reciprocating rocking motion from mechanism hereinafter described. The rock-shaft 29 has two lever-arms 30 secured thereto, and these lever-arms 30 are pivotally connected with two 85 valve-operating bars or rods 31, as shown in Figs. 13 and 20, which are connected at one end of the machine by the cross-bar 32, as shown in Fig. 20, and have each a series of links 33.

The filling-tubes are designated at 34, one for each bottle. On one side of each of said tubes 34 is an ear-piece 35, from which extends a supporting-arm 36. Each link-bar 33 is pivoted at one of its ends to the end of 95 one of these supporting-arms 36 and at the other of its ends to one of the valve-operating bars 31. Each filling-tube 34 has at its top one of said bottling-valves 27, the detail of whose construction is shown in Fig. 11, where it is seen that the upper opening or bore of the valve-chamber incloses and fits upon the port or tubular extension 16 of the socket 15 of the bottom plate 13 of the tank 4. The valve-chamber also has at or near its 105 lower end the circumferential enlargement or knurl 38, and the lower end of the valve-chamber abuts the upper end of the filling-tube 34, the two being flexibly joined by means of the rubber sleeve or collar 39, as fully shown in Fig. 11. Said valve-chamber has at one side a cylindrical extension and a stuffing-box 40 (shown in Fig. 11) of the usual construction and requiring no special description. The bottling-valve 27 moves in, 110 and out of cylindrical extension 41 and across the bore of the valve-chamber, being seated in a groove in said chamber and operated by a valve-stem 42, the latter pivotally connected by its ears 43 to one of the link-bars 33 of 115 the series above described. In said Fig. 11 is also shown the lower portion of the filling-tube 34, which extends very loosely through the tubular barrel or portion 44 of an annular centering-bell 45. Two annular flanges 120 46 and 47 extend from said barrel 44. A vertically-movable bell-carrying frame 48 has openings for the tubular barrels of the centering-bells, respectively, and said flanges 46 and 47 serve to limit the vertical movement 125 of said bells, as will presently be described.

The bell-carrying frame 48 is provided with two tubes 49, Fig. 3, in which a disk 50 is movable, said disk being made with a stem or rod.

51. The frame 48 at the portion where each of said tubes 49 passes loosely through it is made with an annular boss 52, beneath which is a circular recess, (shown in diametrical section in Fig. 3,) and the lower end of the tube 49 has an annular flange 53, which fits loosely in said circular recess. The rod or stem 51 is fastened at its upper end to the bottom plate 13 of the tank 4. Two chains 54 are 5 fastened at their upper ends to said bottom plate 13 and are secured at their lower ends to the bell-carrying frame 48, as shown in Figs. 1, 4, and 18.

The frame or standard 1 has two forwardly curved legs 55, in which is loosely mounted a rock-shaft 56. At one end of said shaft 56 is a handle or lever 57, whose lower end is provided with a collar 58, which is fastened to said shaft by a spline 59. A quadrant-shaped arm 60 is fast upon said shaft 56 by a spline, as shown in Fig. 1, or otherwise in or through the collar 58. On the standard or frame 1 are guides or ways 61.61, Fig. 2, between which is mounted and movable in a vertical direction a shelf-supporting slide 62, from the upper part of which two brackets 63 extend forward horizontally, constituting a shelf or bottle-carrier. A metallic or other strap 64, Fig. 1, is secured on the periphery 15 of the quadrant arm 60, at the lower end of the latter, and is attached at its opposite end to the slide 62 at about the point designated 65 in Fig. 1. Another metallic or other strap 64^a, Fig. 4, is secured on the upper end of the 20 periphery of said quadrant arm and is attached at its opposite end to the bottom of the slide 62. (See Figs. 4 and 14.) A projection or arm 66 extends rearwardly from near the bottom of said slide, and a chain 67 25 is fastened thereto, Fig. 14. This chain passes up over a pulley 68, which is mounted in brackets 69 from the frame or standard, and at the end of the chain is the weight 70. On the upper rear portion of each of the curved 30 legs 55 is a guide-plate 71, fastened in position by screws. The guide proper consists of a rib 72, Figs. 2 and 7, having a rectangular bend 73, and its forward end is flared somewhat, as plainly seen in Fig. 7. As shown in 35 Fig. 8, the hole or aperture 74 is somewhat larger than the bolt 75, thus allowing a certain play or adjustability to accommodate boxes or crates of slightly-different sizes.

A box or crate 76 is set upon the brackets 55 40 63 and pushed back until its rear corners are guided, by means of the ribs 72 of the guide-plates 71, into the proper position. This crate contains the bottles which are to be filled. In the drawings there are shown four rows of 45 bottles, six in each row. By moving the handle or lever 57 from the position shown in Fig. 1 toward the front ninety degrees the shaft 56 is correspondingly turned and the quadrant arm thereon, and by the strap connection 50 from the quadrant arm to the slide 62 the latter is raised, thereby lifting its brackets and the crate of bottles from the position shown

in Figs. 1 and 4 to the position shown in Fig. 13. The crate or box 76 is divided by partitions 77 into square compartments of the proper size to receive the bottles, as clearly shown in Figs. 4 and 13.

In Fig. 9 is seen a keg 78, which contains the beer or other liquid to be bottled and which constitutes the source of supply. The keg 78 rests upon supports 79 and is provided with a venting device 80, having two divergent pipes 81 and 82. A valve 83 closes said venting device when desired. From each of the pipes 81 and 82 is a hose or flexible tube 84 or pipe, (marked 84 and 85, respectively,) these pipes shown in Fig. 9 being continuous with the pipes similarly marked and designated in Fig. 4. The pipe or hose 84 at its lower end is fitted upon a tube 86, which extends 85 up through the rim or frame 7 of the tank 4. The hose or pipe 85 at its lower end fits upon the upper tubular portion of that part of the mechanism which I call the "foam-controller," (marked 87 in Fig. 4.) The lower tubular portion of the foam-controller is screw-threaded, as seen in Fig. 5, and is engageable with an interiorly-screw-threaded bent tube 88 of the measuring-tank 89. (Shown in Fig. 21.)

The measuring-tank 89 is cylindrical, open at the top and closed at the bottom, except where it has the discharge-tube 90, as seen in Fig. 21. It has the curved pipe 88 and also the annular flange 92, extending outwardly, 100 and the annular flange 93, extending inwardly. A ring 94, with a short tubular extension, fits into the measuring-tank 89, and said ring is secured by bolts 95 to the flange 92 of said tank. A movable member, which I designate 105 as the "displacement-piston," is shown at 96 and consists of an open-mouthed cylinder having a closed bottom, from the center of which bottom a tube 97 extends upward, whose bore is screw-threaded. The sides of 110 this cylinder bear against and are in contact with said tubular extension of the ring 94 and with the edge of the internal flange 93 of the measuring-tank, as seen in Fig. 21. A bent yoke 98 is secured by screws to the upper 115 portion of the measuring-tank 89 on opposite sides thereof, Figs. 1 and 4, and extends over the center of the displacement-piston diametrically. A screw-rod 99, mounted in said yoke 98, passes down into and engages with 120 the screw-threaded tube 97 of the displacement-piston. Said screw-rod 99 is provided with a crank and handle 100 at its upper end.

As seen in Fig. 21, a tube or pipe 101 enters the bottle-filling tank 4, near the bottom thereof, on one side, and a branch tube 102 extends from said tube 101 up into the discharge-tube 90 of the measuring-tank 89. The tube 101 has the two valves 103 and 104 arranged and operating, as will presently be 125 described, in such a manner that when one of these valves is open the other is shut. A hose or flexible pipe 105 fits upon the end of said tube 101, as shown in Fig. 4, and its op-

posite end fits upon a short metallic tube 106, Fig. 10.

In Fig. 10 is shown a curved tube 107, screw-threaded at both ends, one end being engaged by a screw-threaded collar 108, provided with a flange 109, which is engageable with a flange 110 of the short tube 106, so that said tubes are drawn into abutment with each other. On the other screw-threaded end of said curved tube 107 is a collar 111, engageable therewith by its own screw-threaded bore. This curved tube 107 has a valve 112 about midway its length, and at about the center of its curve is a projection or boss 113. In the keg 78 is the usual bung-hole, with a conical metallic ring therein. A tubular bung-starter 114 has an external shoulder, and said curved tube is also internally shouled for the reception of the inner end of the bung-starter, the two being engaged by means of screw-threads, as shown in Fig. 10. A rubber ring 115 surrounds the bung-starter and lies between the collar 111 and the edge or flange of the iron bung-ring 116. The foam-controller has a top portion 117, Fig. 5, with a bent neck or tube, and a lower disk or plate 118, with a central tube or pipe 119. Rods or bolts 120 extend from the top to the bottom and hold them together. A cylindrical glass tube or receptacle 121 is held between the top portion 117 and the disk 118, being provided at top and bottom with packing-rings (shown in Fig. 5 by heavy lines) and forming tight joints. In the lower tube 119 is secured a pipe or tube 122, having two extensions 123, on the top of which is a centrally-perforated disk 124, Fig. 6. On the top of this disk 124 rests another disk 125, Fig. 5, having a stem 126, which passes down through the central perforation of the disk 124. (Shown in Fig. 6.) A rubber or other bulb or float-valve 127, with a hemispherical end, is supported by said disk 125 and fastened thereto.

In Figs. 12, 14, and 15 the mechanism on the back of the machine is shown. A central vertical rod 128 is fastened at its bottom to the projection or arm 66 of the slide 62 and at its top is supported and guided by the post 129, Fig. 14. It is also centrally supported by a tubular aperture in the boss 130, extending from the frame or standard 1. A cross-bar 131 is adjustably mounted on said central rod 128 by means of the collar 132 and set-screw 133 and has studs 134 near its ends, as shown in Figs. 12 and 15. Said central rod also has the fixed arms 135, 136, and 137, extending therefrom at right angles and arranged and located as shown in Figs. 12 and 15. On studs or pivots 138 139 are mounted U-shaped arms or slotted cams 139 139, on the tubular barrel of which and movable thereon, respectively, are the arms or levers 140 140. From each arm or lever 140 and pivotally connected therewith is a rod 141. Each rod 141 at its top is pivotally connected with a lever or crank-arm 142, which is fast upon one of the rock-shafts 20, which extend in and across the bottle-fill-

ing tank, as illustrated in Figs. 15, 16, and 18. Each of the fixed arms 135, 136, and 137 has a stud-pin at the outer extremity thereof. 70

On a stud or pivot 143 is a U-shaped arm or slotted cam 144, on the tubular barrel of which and movable therewith is an arm or lever 145. A link or rod 146 is pivoted at the end of the lever 145 at one end and at its opposite end is pivoted to a crank or arm 147, which operates and turns the stem 37, Fig. 19, of the valve 104 of the supply pipe or tube 101, Fig. 18. 75

On the stud or pivot 148 is a U-shaped arm 80 or slotted cam 149; on the tubular barrel of which and movable therewith is an arm or lever 150. A link or rod 151 is pivoted at the end of the lever 150 at one end and at its opposite end is pivoted to a crank or arm 152, 85 which operates or turns the stem 91, Fig. 19, of the valve 103 of the supply pipe or tube 101, Fig. 18.

A U-shaped arm or slotted cam 154 is mounted on the rock-shaft 29, Fig. 20, and is 90 engaged by the stud of the cross-arm 135. This rock-shaft 29 reciprocates the valve-actuating rods 31 of the bottling-valves 27.

In Figs. 16 and 17 is shown a holding device to enable the lifting-fingers 24 to maintain 95 the divider 19 in its elevated position. This consists of a spring 155, bent, as shown, and fastened at its top to the upper part of the bottle-filling tank 4. The edge of the finger 24, near the fulcrum or pivot thereof, is flattened, and when said finger is in the position illustrated in Fig. 16 the free lower end of the spring 155 presses against said portion of the finger with sufficient force to serve as a means of holding said finger in said position. When, 105 however, the divider descends, as is illustrated in Fig. 17, the finger 24 moves away and out of contact with said spring.

Having thus described the different parts of my improved bottle-filling machine, I will 110 now proceed to explain its operation.

The bung-starter 114 is inserted inside the metallic tube or ring 116. (See Fig. 10.) Repeated blows by a mallet or hammer upon the projection or boss 113 of the curved tube 107 115 forces the bung-starter 114 against the bung and drives said bung into the keg. By turning up the collar 111 upon the upper end of the curved tube 107 the rubber ring 115 between said collar 111 and the metallic ring 116 is compressed and forms a packing. The bung-starter and the bung-ring are held together by their frictional contact. The vent is then driven in, and the keg 78 of beer or other liquid which is to be bottled is placed 120 in position, bung down, upon its supports 79, Fig. 9, in a plane higher than that of the measuring-reservoir 89 and tank 4 and all pipe connections made. The valves 112 and 83 are then turned to allow the flow of liquid 125 through the pipes 105 and a return of foam through pipe 85 and a return of the gases through pipe 84. The hose-pipes 84 and 85 and 105 of Fig. 10 are, as before explained, 130

continuous of the hose-pipes 84, 85, and 105 of Fig. 4. The valve 103 of the supply-pipe 101 being open and the valve 104 of the same pipe being closed, the liquid flows by gravity 5 from the keg 78 through the pipes 107, 106, 105, and 101 and the branch pipe 102 into the measuring-tank 89. The quantity of liquid to be bottled at one operation of the handle or lever 57 and divided equally in all the bottles 28 of the crate 76 is determined exactly 10 by means of the displacement-piston. By turning the crank 100, Fig. 21, the screw-rod 99, engaging with the tube 97, is operated and the displacement-piston is moved toward 15 or from the bottom of the measuring-tank 89, the liquid filling whatever space is between. In the flow of the liquid the foam comes first and fills the measuring-tank 89, Fig. 21, and rises up into and through the curved tube 88 20 and thence into the foam-controller 87, Fig. 5. The foam rises up through the pipe 122, through the spaces between the two extensions 123, into the glass receptacle 121, up through the bent neck or tube 117, along the 25 hose 85, tube 82, and vent-pipe 80 into the keg again, Fig. 9. The float-valve 127, so long as foam only is passing up through the foam-controller, remains in the position shown in Fig. 5, owing to its superior specific gravity; 30 but as soon as the foam has passed through the foam-controller and the solid liquid comes and rises in the glass cylinder or receptacle 121 the buoyancy of the float-valve 127 causes said valve to rise from the position shown in 35 solid lines in Fig. 5 to the position shown in dotted lines in said figure, thereby closing the belled or flaring end of the neck or tube 117 and at the same time preventing the return of the solid liquid back into the keg through 40 pipe 117. The crate 76 of bottles is placed upon the brackets 63 of the lifting device and by means of the guides 71 (shown in Figs. 1, 2, 7, and 8) is accurately positioned when pushed back to the full extent, the flaring or 45 outwardly-bent ends of the ribs 72 directing such movement. The mouths of the bottles 28 are thus in position exactly (or nearly so) beneath the centering-bells 45, respectively. The attendant then moves the handle or lever 57 from the position shown in Fig. 1 forward ninety degrees, thereby partially turning the shaft 56 and the connected quadrant arm 60 and by means of the strap connection 50 of the quadrant and slide causing said slide to rise along the guides or ways 61 61. The shelf or brackets 63, with the bottle-crate 76 thereon, rises from the position shown in Figs. 1 and 4 to the position shown in Fig. 13. The upper end of the neck of each bottle rising 55 into contact with the centering bell immediately above it, Fig. 11, is by said bell directed as the upward movement of the crate continues into such position that the lower end of the filling-tube 34 enters the neck of 60 the bottle, the flexible connection 39 allowing the filling-tube 34 to accommodate itself to the bottle. The continued rise of the bottles

and crate causes the bottles to receive the filling-tubes 34, respectively, till the lower end of said tubes 34 are quite near the bottom of the bottles, as illustrated in Fig. 13. During this rise of the bottles and crate the centering bells 45, carried by the upper ends of the bottle-necks, have moved upward on the outside of their respective filling-tubes 34. 70 Said bells 45 by means of their flanges 46 47 communicate said upward movement to the bell-centering frame, and the said frame 48 is directed and limited to a true vertical movement by means of its guiding device. (Shown 80 in Figs. 4, 13, 14, and 18 and in longitudinal section and front elevation in Fig. 3.) As the frame 48 rises it moves up along the tubes 49 until it comes in contact with the upper flanges 46 of said tubes, and thereafter, continuing to rise, the frame 48 lifts the tubes 49 by said flanges 46 up along the rods or stems 51. By the turning of the valves 103 and 104, Fig. 21, as I will presently explain, the liquid in the measuring-tank 89 and whose 90 quantity has been already accurately measured, as above-described, flows from said tank 89 through the branch pipe 102 and supply-pipe 101 into the bottle-filling tank 4, the turning of the valve 103, as shown in Fig. 18, 95 preventing any flow from the keg 78 or source of supply into the measuring-tank 89 at this time. The liquid so discharged from the measuring-tank 89 into the bottle-filling tank finds its level in the latter tank. While the 100 liquid is flowing into the bottle-filling tank 4 the divider 19 is in the elevated position therein, (shown in Fig. 18,) the liquid flowing under said divider through the open bottom thereof. The pressure of the spring 155, as 105 shown in Fig. 16, holds the divider in its elevated position. The divider is then lowered, as hereinafter described, and divides the body of liquid in the tank 4 into as many equal parts as there are compartments in the divider. The divider has the bottom edges of its 110 four sides and of its cross-partitions resting (when lowered into the position indicated by dotted lines in Fig. 18) upon the upper edges of the respective sockets 15 in the bottom plate 115 13 of the tank 4. When the body of liquid has thus been divided, it is discharged into the bottles beneath by the simultaneous operation of all the bottling-valves, which are illustrated in Figs. 13, 18, and 20 and one of 120 which is shown in section in Fig. 11. Each bottling-valve is moved out of the position shown in Fig. 11, where it is seen as closing the filling-tube 34 into the recess in the cylindrical extension, as hereinafter explained, 125 whereupon the entire quantity of liquid contained in each one of the compartments of the divider 19 and the socket or depression adjacent thereto in the bottom plate 13 of the tank 4 is discharged through the filling-tube extending from such socket into the bottle directly beneath. The attendant then 130 reverses the movement of the handle or lever 57, pushing it back to its former position, (shown

in Fig. 1,) thereby lowering the bottles and crate and the brackets supporting them from the position shown in Fig. 13 to the position shown in Fig. 4. This return is caused by the 5 reverse movement of the lever 57 and strap. The bell-carrying frame 48 then descends by its weight till it hangs suspended from the ends of the chains 54, as at first. The bottle-necks descend out of engagement with the 10 centering-bells, and the crate or rack of bottles is removed from the brackets, all the bottles having been equally filled with the liquid from the tank 4. The divider 19 then rises to its former position by the operation 15 of the fingers 24, the bottling-valves close, the valve 104 closes, and the valve 103 opens, thus supplying the tank 89 with the proper quantity of liquid to be bottled by the next operation of the machine. It remains now 20 simply to explain how these various valves are automatically operated and the divider made to rise and descend at the proper times. As the slide 62 moves up and down it carries with it the rod 128. The rod 128 in rising 25 from the position shown in Fig. 12 causes the cross-bar 131 thereon to rise with it, and the studs of said cross-bar engage with and turn the U-shaped arm or slotted cams 139, thus moving the arms or levers 140, and thereby 30 pulling down the rods 141. These rods 141 operate the levers or crank-arms 142 of the rock-shafts 20, which extend across the bottle-filling tank inside it. As seen in Fig. 18, these rock-shafts 20, by their respective fingers or cam-levers 24, serve to raise the 35 divider 19, Fig. 21, when moving in one direction or to lower the divider when moving in the opposite direction, as fully indicated in Figs. 16, 17, and 18. The fixed arm 135 on 40 the rod 128, as shown in Fig. 12, engages by its pin the slotted lever or cam 154, which is moved from the position shown in Fig. 12 to the position shown in Fig. 15, thereby rocking 45 the tubular barrel of said lever or arm and with it the connected link 30, Fig. 20. Said link, being pivotally connected with the rod 31, Fig. 20, moves the latter from the position shown in Fig. 12 to the position shown in Fig. 15. The links 33 are thus carried 50 from the position shown in solid lines in Fig. 20 to the position shown in dotted lines in said figure and so open the bottling-valves, which allows the liquid to flow from the bottle-filling tank 4 through the filling-tubes 34 55 into the bottles. The fixed arm 136 on the rod 128 in rising therewith moves the slotted lever or cam-arm 144 from the position shown in Fig. 12 to the position shown in Fig. 15, thereby, through the arm 145, rod 146, and 60 crank 147, turning the valve 104, which admits the liquid from the measuring-tank 89 to the bottle-filling tank 4. The fixed arm 137 on the rod 128 in moving therewith moves the slotted lever or cam-arm 149 (the stud- 65 pin of this arm being on the opposite side of the arm, so that the cam will not engage with

stud-pin on arm 136) from the position shown in Fig. 12 to the position shown in Fig. 15, thereby, through the arm 149, rod 151, and crank 152, turning the valve 103, which stops 70 the flow of the liquid from the source of supply to the measuring-tank 89. The valves and valve-operating mechanism are in the relative positions shown in Fig. 12 when the machine is in the position shown in Figs. 1 75 and 4, and they are in the position shown in Fig. 15 when the machine is in the position shown in Fig. 13. In moving the handle or lever 57 from the position shown in Fig. 1 ninety degrees the valve 103 first closes, shutting off the supply from the keg 78 to the measuring-tank 89 and next opening the valve 104 to allow the liquid to flow from the measuring-tank 89 into the bottle-filling tank 4, and then lowering the divider 19 in the tank 85 4, and then drawing out the bottling-valves 27 to allow the liquid to flow from the tank 4 into the bottles. When the handle or lever 57 is moved back from its forward position, the bottling-valves 27 are first operated, then 90 the divider 19 is raised in the tank 4, then the valve 104 is closed, and, finally, the valve 103 is opened.

By means of the hose 84 the gas causing the effervescence in the liquid and which rises 95 from the liquid while in the bottle-filling tank passes up from said tank into the keg 78 and so is preserved.

In this system of bottling the liquid is drawn 100 from the bottom of the keg or source of supply and is delivered into the bottom of the measuring-tank, and then is drawn from the bottom of the measuring-tank into the bottom of the filling-tank, and then is drawn from the bottom of the filling-tank through the 105 tubes into the bottom of the bottles, thus reducing the amount of foam.

I claim as a novel and useful invention and desire to secure by Letters Patent—

1. In a bottle-filling machine, the combination of a tank having a given quantity of liquid therein, and a divider, vertically movable in said tank, through said liquid and having vertical partitions constituting a series of compartments of equal size, open at the bottom, 110 which divider is adapted to rest by the lower edges of its sides and of said partitions upon the bottom of the tank, and to divide the entire quantity of said liquid into as many equal parts as there are compartments in said divider, substantially as specified.

2. In a bottle-filling machine, the combination of a tank adapted to contain a determined quantity of liquid and having its bottom provided with a plurality of discharge-ports arranged in equal spaces, respectively, and a divider which is vertically movable in said tank, and made with vertical partitions to form compartments of equal size and equal in number and corresponding in location with 125 said discharge-ports, and which is adapted to rest upon the bottom of said tank and to di- 130

vide the entire quantity of said liquid into as many equal parts as there are compartments in said divider, together with means for closing and opening said ports, all arranged and operating, to divide the whole of said liquid in the tank into so many equal portions, and to discharge into as many bottles or other receptacles, from said compartments, respectively, the liquid which has been so divided, substantially as described.

3. In a bottle-filling machine, the combination of a tank adapted to contain a quantity of liquid and having its bottom provided with a plurality of discharge-ports, arranged in equal spaces, respectively, a divider of a height exceeding the depth of said liquid and movable within said tank, and made with partitions of the same height to form compartments equal in number and corresponding in location with said discharge-ports and adapted to rest upon the bottom of said tank, and means within the tank for the purpose of lowering said divider through said liquid in the tank to divide the entire quantity thereof into equal parts as many in number as the number of said compartments and thereafter to raise the divider in the tank, substantially as shown.

4. In a bottle-filling machine, the combination of a reservoir to hold the liquid to be bottled, a tank having a bottom formed into a series of sockets or depressions separated from each other by intermediate ridges, ports in the lowest part of said sockets or depressions, respectively, a divider vertically movable in said tank, separated by partitions therein into compartments of equal size and adapted to rest by the bottom edges of its sides and of its partitions upon said ridges, respectively, means for opening and closing said ports and a pipe connection from said reservoir to said tank, with a suitable valve therein, substantially as set forth.

5. In a bottle-filling machine, the combination of a reservoir to hold the liquid to be bottled, a tank having a bottom formed into a series of sockets or depressions separated from each other by intermediate ridges, ports in the lowest part of said sockets or depressions, respectively, a divider within said tank, separated by partitions into compartments of equal size and adapted to rest by the bottom edges of its sides and of its partitions upon said ridges, respectively, means for raising and lowering said divider in the tank, means for opening and closing said ports and a pipe connection between said reservoir and tank, with a suitable valve therein, substantially as specified.

6. In a bottle-filling machine, the combination of a tank having means to receive and discharge a liquid, a divider having compartments and vertically movable in the tank, rotatable shafts properly mounted and extending across said tank from side to side within the same, cam-fingers upon said shafts and friction-rollers mounted upon the ex-

terior of the divider and engageable by said cam-fingers, substantially as described.

7. The combination of a tank, two rotatable shafts mounted in the tank and having each two cam-fingers fastened thereon, four springs secured at their upper ends to the tank within the same and engageable by friction with the cam-fingers, respectively, at or near the inner ends of said cam-fingers, and a divider, made with compartments and provided with friction-rollers at or near its corners, which are supported by said cam-fingers, respectively, substantially as shown.

8. In a bottle-filling machine, the combination of a source of supply, a reservoir, a pipe from the source of supply to the reservoir with a valve in said pipe, a tank having discharge-pipes extending from the bottom thereof, a pipe from the reservoir to the tank and a valve in said pipe, a divider in the tank, two rotatable shafts in the tank with cam-fingers arranged and adapted to move the divider vertically in the tank, a series of horizontally-arranged valves beneath the tank adapted to open and close said discharge-pipes from the tank, a bar to operate the valves last aforesaid, a vertical rod properly supported on the back of the machine, an operating-lever and means between said operating-lever and vertical rod to communicate motion from the former to the latter, a crank-arm on the rear end of each of said rotatable shafts, two slotted lever-arms pivotally mounted on the back of the machine and each having a hub and a crank-arm therefrom, a rod from each of the crank-arms last aforesaid to the crank-arms of said rotatable shafts, respectively, a slotted lever-arm pivotally mounted on the back of the machine and having a hub and a crank-arm therefrom, the latter being pivotally connected with the valve-operating bar aforesaid, a slotted lever-arm pivotally mounted on the back of the machine having a hub and a crank-arm therefrom, a crank-arm on the valve first mentioned, a rod between the two crank-arms last aforesaid, a slotted lever-arm pivotally mounted upon the back of the machine having a hub and a crank-arm therefrom, a crank-arm on the valve secondly above named, a rod between the two crank-arms last aforesaid, four cross-arms fastened upon the vertically-movable rod, all provided with stud-pins at their ends, respectively, the lowest cross-arm engageable with the two slotted lever-arms first aforesaid and adapted to operate the mechanism for raising and lowering the divider in the tank, the next cross-arm above engageable with the slotted arm connected with the mechanism for operating the series of valves beneath the tank, the next cross-arm above engageable with the slotted lever-arm connected with the mechanism for operating the valve between the reservoir and tank, and the top cross-arm engageable with the slotted lever-arm connected with the mechanism to operate the

operating-lever and vertical rod to communicate motion from the former to the latter, a crank-arm on the rear end of each of said rotatable shafts, two slotted lever-arms pivotally mounted on the back of the machine and each having a hub and a crank-arm therefrom, a rod from each of the crank-arms last aforesaid to the crank-arms of said rotatable shafts, respectively, a slotted lever-arm pivotally mounted on the back of the machine and having a hub and a crank-arm therefrom, the latter being pivotally connected with the valve-operating bar aforesaid, a slotted lever-arm pivotally mounted on the back of the machine having a hub and a crank-arm therefrom, a crank-arm on the valve first mentioned, a rod between the two crank-arms last aforesaid, a slotted lever-arm pivotally mounted upon the back of the machine having a hub and a crank-arm therefrom, a crank-arm on the valve secondly above named, a rod between the two crank-arms last aforesaid, four cross-arms fastened upon the vertically-movable rod, all provided with stud-pins at their ends, respectively, the lowest cross-arm engageable with the two slotted lever-arms first aforesaid and adapted to operate the mechanism for raising and lowering the divider in the tank, the next cross-arm above engageable with the slotted arm connected with the mechanism for operating the series of valves beneath the tank, the next cross-arm above engageable with the slotted lever-arm connected with the mechanism for operating the valve between the reservoir and tank, and the top cross-arm engageable with the slotted lever-arm connected with the mechanism to operate the

operating-lever and vertical rod to communicate motion from the former to the latter, a crank-arm on the rear end of each of said rotatable shafts, two slotted lever-arms pivotally mounted on the back of the machine and each having a hub and a crank-arm therefrom, a rod from each of the crank-arms last aforesaid to the crank-arms of said rotatable shafts, respectively, a slotted lever-arm pivotally mounted on the back of the machine having a hub and a crank-arm therefrom, a crank-arm on the valve first mentioned, a rod between the two crank-arms last aforesaid, a slotted lever-arm pivotally mounted upon the back of the machine having a hub and a crank-arm therefrom, a crank-arm on the valve secondly above named, a rod between the two crank-arms last aforesaid, four cross-arms fastened upon the vertically-movable rod, all provided with stud-pins at their ends, respectively, the lowest cross-arm engageable with the two slotted lever-arms first aforesaid and adapted to operate the mechanism for raising and lowering the divider in the tank, the next cross-arm above engageable with the slotted arm connected with the mechanism for operating the series of valves beneath the tank, the next cross-arm above engageable with the slotted lever-arm connected with the mechanism for operating the valve between the reservoir and tank, and the top cross-arm engageable with the slotted lever-arm connected with the mechanism to operate the

operating-lever and vertical rod to communicate motion from the former to the latter, a crank-arm on the rear end of each of said rotatable shafts, two slotted lever-arms pivotally mounted on the back of the machine and each having a hub and a crank-arm therefrom, a rod from each of the crank-arms last aforesaid to the crank-arms of said rotatable shafts, respectively, a slotted lever-arm pivotally mounted on the back of the machine having a hub and a crank-arm therefrom, a crank-arm on the valve first mentioned, a rod between the two crank-arms last aforesaid, a slotted lever-arm pivotally mounted upon the back of the machine having a hub and a crank-arm therefrom, a crank-arm on the valve secondly above named, a rod between the two crank-arms last aforesaid, four cross-arms fastened upon the vertically-movable rod, all provided with stud-pins at their ends, respectively, the lowest cross-arm engageable with the two slotted lever-arms first aforesaid and adapted to operate the mechanism for raising and lowering the divider in the tank, the next cross-arm above engageable with the slotted arm connected with the mechanism for operating the series of valves beneath the tank, the next cross-arm above engageable with the slotted lever-arm connected with the mechanism for operating the valve between the reservoir and tank, and the top cross-arm engageable with the slotted lever-arm connected with the mechanism to operate the

operating-lever and vertical rod to communicate motion from the former to the latter, a crank-arm on the rear end of each of said rotatable shafts, two slotted lever-arms pivotally mounted on the back of the machine and each having a hub and a crank-arm therefrom, a rod from each of the crank-arms last aforesaid to the crank-arms of said rotatable shafts, respectively, a slotted lever-arm pivotally mounted on the back of the machine having a hub and a crank-arm therefrom, a crank-arm on the valve first mentioned, a rod between the two crank-arms last aforesaid, a slotted lever-arm pivotally mounted upon the back of the machine having a hub and a crank-arm therefrom, a crank-arm on the valve secondly above named, a rod between the two crank-arms last aforesaid, four cross-arms fastened upon the vertically-movable rod, all provided with stud-pins at their ends, respectively, the lowest cross-arm engageable with the two slotted lever-arms first aforesaid and adapted to operate the mechanism for raising and lowering the divider in the tank, the next cross-arm above engageable with the slotted arm connected with the mechanism for operating the series of valves beneath the tank, the next cross-arm above engageable with the slotted lever-arm connected with the mechanism for operating the valve between the reservoir and tank, and the top cross-arm engageable with the slotted lever-arm connected with the mechanism to operate the

valve between the source of supply and the reservoir, all arranged and operating substantially as and for the purpose specified.

9. In a bottle-filling machine the combination of a tank provided with discharge-pipes extending from the bottom thereof, valves in each of said discharge-pipes and means adapted to connect said valves for simultaneous movement, an operating-lever mounted on the side of the machine, a vertically-movable rod and connecting means to operate said rod from the lever, a cross-bar on said rod with a stud-pin at the end thereof, a slotted lever-arm pivotally mounted on the back of the machine and having a hub and a crank thereon and a connection between said crank and the means for operating the valves of the discharge-pipes, all arranged and operating substantially as shown and for the purpose specified.

10. In a bottle-filling machine, the combination of a tank with discharge-ports, two rotatable shafts mounted in the tank across the same, cam-fingers on said shafts, a partitioned divider with friction-rollers and supported on said cam-fingers, a crank on the end of each shaft, an operating-lever mounted on the side of the machine, a vertically-movable rod and connecting means to operate said rod from the lever, two slotted lever-arms pivotally mounted on the back of the machine each having a hub and a crank therefrom and a rod from each of the cranks last aforesaid to the cranks of the shafts, respectively, all arranged and operating substantially as shown and for the purpose specified.

11. In a bottle-filling machine, the combination of a filling-tank, a plurality of discharge-pipes from said tank at the bottom thereof, valves in each of said pipes, respectively, connecting means adapted to operate all said valves simultaneously, a reservoir, a communication from the reservoir to the tank with a valve arranged to open or close said communication, a divider having an open bottom and vertically movable in the tank and separated into equal compartments corresponding in number and location with said discharge-pipes, means for vertically moving said divider, a support for a plurality of bottles and a lever provided with means adapted to simultaneously raise said bottles by means of said support into contiguity with said discharge-pipes, respectively, lower the divider, close the valve to the communication between the reservoir and tank, and open the valves of said discharge-pipes, substantially as specified.

12. In a bottle-filling machine, the combination of a source of supply, a reservoir, a pipe from the source of supply to the reservoir with a valve in said pipe, a filling-tank, a plurality of discharge-pipes from said tank at the bottom thereof, valves in each of said pipes, respectively, connecting means adapted to operate all said valves simultaneously, a communication from the reservoir to the tank

with a valve arranged to open or close said communication, a divider having an open bottom and vertically movable in the tank and separated into equal compartments corresponding in number and location with said discharge-pipes, means for vertically moving said divider, a support for a plurality of bottles and a lever provided with means adapted to simultaneously raise said bottles into contiguity with said discharge-pipes, respectively, close the valve in the pipe from the source of supply to the reservoir, open the valve in the pipe from the reservoir to the tank, lower the divider and open the valves in the discharge-pipes, substantially as described.

13. In a bottle-filling machine, the combination of a tank, a plurality of discharge-pipes from said tank at the bottom thereof, valves in each of said pipes, respectively, connecting means adapted to operate all said valves simultaneously, a reservoir, a communication from the reservoir to the tank with a valve arranged to open or close said communication, a divider having an open bottom and vertically movable in the tank and separated into equal compartments corresponding in number and location with said discharge-pipes, means for vertically moving said divider, a support for a plurality of bottles and a lever provided with means adapted to simultaneously lower said bottles by means of said support, close the valves of the discharge-pipes, raise the divider, and open the valve from the reservoir to the tank, substantially as set forth.

14. In a bottle-filling machine, the combination of a source of supply, a reservoir, a pipe from the source of supply to the reservoir with a valve in said pipe, a tank, a plurality of discharge-pipes from said tank at the bottom thereof, valves in each of said pipes, respectively, connecting means adapted to operate all said valves simultaneously, a communication from the reservoir to the tank with a valve arranged to open or close said communication, a divider having an open bottom and vertically movable in the tank and separated into equal compartments corresponding in number and location with said discharge-pipes, means for vertically moving said divider, a support for a plurality of bottles and a lever provided with means adapted to simultaneously lower said bottles by means of said support, close the valves in the discharge-pipes, raise the divider, close the valve in the pipe between the reservoir and tank and open the valve in the pipe between the reservoir and source of supply, substantially as specified.

15. In a bottle-filling machine, the combination of a reservoir, a valve for filling said reservoir from a suitable source of supply, a tank, a plurality of discharge-pipes from said tank at the bottom thereof, valves in each of said pipes, respectively, connecting means adapted to operate all the last-mentioned

valves simultaneously, a communication from the reservoir to the tank with a valve arranged to open or close said communication, a divider having an open bottom and vertically movable in the tank and separated into equal compartments corresponding in number and location with said discharge-pipes, means for vertically moving said divider, a support for a plurality of bottles and a lever which simultaneously lowers said bottles by means of said support from said discharge-pipes, raises the divider and opens the valve for filling the reservoir, substantially as described.

15 16. In a bottle-filling machine, the combination of a tank, a plurality of discharge-pipes from said tank at the bottom thereof, valves in each of said pipes, respectively, connecting means adapted to operate all said valves simultaneously, a reservoir, a communication between the reservoir and tank with a valve arranged to open and close said communication, a divider having an open bottom and vertically movable in the tank and separated into equal compartments corresponding in number and location with said discharge-pipes, means for vertically moving said divider, a source of supply with a communica-

tion therefrom to the reservoir having a valve therein, a vertically-movable bottle-carrying table, a swinging operating-lever, through which the table is actuated, a vertically-reciprocating rod, connected with and moving in unison with the table and devices connected with all said valves and made operative by said rod, substantially as specified.

17. In a bottle-filling machine, the combination of a tank having controllable means to supply a liquid to the same, a quantity of liquid in said tank, a divider open at the top and bottom, which is separated into vertical compartments of equal size and which is movable vertically into and through the whole body of said liquid, to divide the entire quantity of said liquid equally into as many parts as there are compartments in said divider, and controllable means in said tank adapted to discharge said liquid therefrom, and so arranged and placed as to correspond in location with the vertical planes of said compartments, respectively, substantially as described.
